UNITED STATES PATENT OFFICE

2,502,796

WALLPAPER PASTING AND TRIMMING
MACHINEChester R. Lamb, Richmond, Ind., assignor of
one-half to Guy W. Alexander, Richmond, Ind.

Application February 11, 1946, Serial No. 646,933

3 Claims. (Cl. 91—14)

1

The principal object of the invention is the provision of a machine which reduces the time required in preparing wall paper for application.

Another object is the provision of a machine which provides means uniformly spreading paste on wall paper with means located thereon for uniformly trimming the paper simultaneously with the application of the paste thereto.

Further objects and advantages of the invention will be apparent in the course of the following description, and that which is new will be pointed out in the appended claims.

The most satisfactory manner of carrying out the principles of the invention in a practical and efficient manner is shown in the accompanying three sheets of drawings, in which:

Figure 1 is a side elevation of the machine and shows a roll of wall paper therein.

Figure 2 is a front elevational detail of the machine, taken from line 2—2 of Figure 1, and with the roll of wall paper being omitted therefrom.

Figure 3 is a rear elevation of the machine, as taken from line 3—3 of Figure 1.

Figure 4 is a detail plan view of the machine as taken from line 4—4 of Figure 1.

Figure 5 is a partial plan view showing the manner of mounting the paste trough and the paste pick-up roller in the frame.

Figure 6 is a detail vertical section through the end portion of the paste trough and the paste pick-up roller, as taken on line 6—6 of Figure 5.

Figure 7 is a detail section through the cutter bar, taken on line 7—7 of Figure 4.

Figure 8 is a partial detail plan showing one of the adjustable paper guides.

Figure 9 is a detail vertical section through one of the adjusting screws, as taken on line 9—9 of Figure 8.

Figure 10 is a detail section through the rear frame member, taken on line 10—10 of Figure 3, and showing the automatic stop member.

Figure 11 is a detail section similar to that shown in Figure 10 except with the stop member being shown in retracted or disengaged relation, and as setting on the surface of a table or other supporting surface.

Figure 12 is an enlarged partial side elevation showing the paste trough, the paste pick-up roller, and the trimming roller.

Figure 13 is a partial front elevation of the members shown in Figure 12, and as taken from line 13—13 of Figure 12.

Like characters designate like parts throughout the several views.

2

In order that the advantages of the invention may be more fully understood, I will now take up a detailed description thereof in which the same will be more fully described.

Referring now to the drawings in detail, A indicates a table or other support for the machine, and B designates the wall paper.

The machine is provided with a base comprising an angle member 1 which extends along each side and across the rear portion of the machine, and which is adapted to provide a support for the machine on a table or other surface A. A U-shaped uprightly-disposed frame 2 is rigidly secured to the side frame members 1 near the rear portions thereof with the same extending across from one side to the other of the machine.

A cutter bar member 3 is provided with a supporting frame 4 located at and rigidly secured to the forward ends of the frame member 1. The supporting frame 4 extends upwardly from the base frame 1 and extends across the forward end of the machine. A hinge 5 is provided at one end of the cutter bar 3, with the opposite end thereof being removably secured to its support 4 by means of the bolt 6, the purpose of the hinge 5 and bolt 6 being further set forth hereinafter.

Each side of the machine is provided with a bar member 7 which has its forward end rigidly secured to the cutter bar supporting frame 4, as more clearly shown in Figures 1, 2, 4, 8, and 9. The bar members 7 are further rigidly secured to the respective upwardly extending legs of frame 2, also as shown in Figures 1, 5, 12, and 13. The rear end of each of the members 7 is provided with an angularly-disposed slot 8, the purpose of which will be more fully hereinafter set forth.

A rod member 9 is located near the forward end of the machine and is removably journaled at each end thereof in a slot 10 formed in a respective bar member 7, and is adapted to support a roll of wall paper, as shown in Figure 1.

A paste pan or receptacle 11 is pivotally supported between the side upright members 2 by means of pins 12, with the same being journaled in slots 13 which are formed in the members 2, and with the pins 12 being rigidly secured through respective ends of the pan 11.

A paste roller 14 is rotatably supported within the paste pan 11 by means of a pin 15 concentrically located in each end of the roller. The pins are removably journaled in respective slotted brackets 16 which are secured within the ends of the paste pan 11, as more clearly shown in Figures 5, 6, and 13. A channelled groove 17

is formed around the roller near one end thereof, the purpose of which will be hereinafter set forth.

A contact roller 18 is positioned above paste roller 14 with the shaft 19 thereof being journaled in slots 20 of the vertical frame members 2, as shown in Figures 1, 12, and 13. Each end of the shaft 19 is provided with a channelled groove for the reception of the upper end portion of a respective tension spring 21, with the lower ends of the tension springs being secured through a fastening 22. The springs 21 provide means holding the contact roller against the paste roller 14, and also provide means holding the wall paper B in contact with the paste roller while being passed through the machine. A circular knife 23 is secured to one end of roller 18 and is adapted to extend into the channelled groove 17 of the paste roller 14, and provides means for trimming one edge of the wall paper as the same passes between rollers 14 and 18.

An auxiliary roller 24 is located at the rear portion of the machine, and has a pin 25 in each end thereof which is journaled in a respective slot 8 of the bar member 7. A collar 26 is located at one end of roller 24 and provides means for guiding the length of wall paper as the same passes thereover. It will be noted, by reference to Figures 3 and 4, that the guide collar 26 is positioned in alignment with the knife member 23 of the contact roller 18.

In order to provide means for adjusting the position of the roll of wall paper laterally within the machine, I have provided an adjustable guide bar 27 at each side of the machine, with the same being located within the machine with respect to the side bar members 7, as more clearly indicated in Figures 2, 4, 8, and 9. Each of the guide bars has a pair of brackets 28 secured thereto and into which inner end portions of adjusting screws 29 are revolvably secured. The screws 29 are threaded through the bars 7 and the bosses 30, and have slots formed in the outer ends thereof for adjusting purposes.

A pan adjusting rod 31 is adjustably positioned and suspended from the bars 7, and is located between the pasting roller 14 and the auxiliary roller 24, as shown in Figures 1, 3, 4, 5, and 12. The adjusting rod is adapted to engage lug members 32 which are secured to the rear side of pan 11.

A stop bar member 33 is secured to the rear frame member 1 by means of rivets or by other suitable means 34. It will be noted, from Figures 3, 10, and 11 that the rivets extend through elongated apertures formed in the bar 33 which permits vertical movement of the bar with relation to the frame member. In use, the machine is usually placed at one end of a table or other support A with the bar 33 extending below the lower edge of the frame member 1, as shown in Figure 1 and 10, and preventing movement of the machine forwardly as the wall paper is taken therefrom. Figure 11 shows the position assumed by the stop bar when the machine is placed on a flat surface and not adjacent an edge thereof.

Operation

In the operation of the machine, the pan 11 is filled to the proper level with paste of the proper consistency. Rod 9 is removed from the machine and inserted longitudinally through a conventional roll of wall paper. The paper is threaded between the paste roll 14 and the contact roll 18, after which the guide bars 27 are adjusted

to their proper positions with relation to the roll of paper to align the same laterally of the machine with relation to the knife member 23. The paper is then passed around the auxiliary roller 24 as shown in Figure 1, and then brought forwardly over the contact roller 18 and between the frame 4 and the cutter bar 3.

As the wall paper is pulled from the machine, the paper, passing between the paste roller and 10 the contact roller, causes these rollers to revolve in the direction indicated by the arrows in Figure 1. As the paper passes over paste roller 14, the paste is transferred from the roller to the under side of the paper. Also, as the paper passes 15 between the contact roller and the paste roller, one edge thereof is trimmed by the knife 23.

When the desired length of paper has been pulled from the machine, the paper is torn off in the usual manner by an upward motion against 20 the cutter bar.

The rear edge of the paste pan 11 forms a scraping means determining the amount of paste 25 adhering to the paper and is adjustable with relation to the paste side of the wall paper as the same travels from the paste roller 14 to the auxiliary roller 24 by means of the adjusting rod 31. The adjustment of the rear edge of the paste pan 11 with relation to the paper provides means governing the amount of paste carried by 30 the paper. If a heavier coating of paste is desired, the rear edge of the pan is lowered with relation to the paper passing thereover. If a thinner coating of paste is desired, the rear edge of the pan is adjusted upwardly by means of rod 35 31, into tighter contact with the under side of the paper, with the excess paste being returned into the pan.

When it is desired to clean the machine, the 40 tension springs 21 are removed from the ends of shaft 19, permitting the contact roller 18 to be lifted upwardly and forwardly out of the slots 20. The paste roller 14 can then be removed from its position within the pan 11 by merely lifting the same upwardly, after which the pan 11 can be removed by an upward and forward movement. It will be further noted also that, due to the paste roller 14 being journaled within the paste pan 11, the roller may be removed with the pan. Auxiliary roller 24 is also removable from the machine by an upward and rearward movement. The cutter bar 3 can be readily accessible for cleaning by removal of bolt 6 which will permit the bar to be swung upwardly by means of the hinge 5. It will be noted that a catch of the eccentric type may be satisfactorily substituted for bolt 6 which will permit of faster action in releasing the one end of the cutter bar 3 for hinged movement.

I desire that it be understood that I am not 60 to be limited to the exact form and arrangements of the parts herein shown and described.

I further desire that it be understood that changes and additions may be provided in the machine for the provision of paper of different 65 widths, insofar as the changes may fall within the scope of the appended claims.

Having now fully shown and described the invention, what I claim, and desire to secure by Letters Patent of the United States, is:

70 1. In a wall paper pasting and trimming machine, the combination of a machine having a rod located therein and adapted to support a roll of wall paper, a paste pan swingably positioned within the machine, a paste roller revolvably 75 positioned within the paste pan, a channelled

groove formed around the paste roller and located near one end thereof, a contact roller mounted above the paste roller, a knife member secured to the contact roller and coinciding with and extending into the channelled groove of the paste roller, with the knife providing means trimming one edge of the paper as the same passes between the contact roller and the paste roller, and adjustable means tilting one edge of the paste pan with relation to the pasted paper passing thereover and governing the amount of paste carried by the paper.

2. In a wall paper pasting and trimming machine, a series of rollers forming guides for paper passing through the machine, a paste pan adjustably supported within the machine, one of said series of rollers extending into the paste pan and having a portion thereof extending into paste carried by the paste pan, means adjustably changing the position of the paste pan, with one edge of the paste pan forming a scraper for removing excess paste from paper passing thereover, and means adjustably positioning the scraper edge of the paste pan with relation to the pasted surface of the paper.

3. In a wall paper pasting and trimming machine, a frame, a paste pan pivotally positioned in said frame, a paste roller journaled within the

paste pan, with the paste pan being removably supported in the frame by means of a pin located in each end of the paste pan extending into adjacent members of the frame, with the rear edge of the pan forming a scraper for excess paste picked up by paper passing over the paste roller, and adjustable means located adjacent the scraping edge of the pan and bringing the scraping edge of the pan into contact with the surface of the paper passing thereover.

CHESTER R. LAMB.
